Primary Examiner — Khawaja Anwar*Assistant Examiner* — Mojtaba Tehrani(74) *Attorney, Agent, or Firm* — Warner Norcross + Judd, LLP(57) **CLAIM**

The ornamental design for an arrow vane, as shown and described.

DESCRIPTION

FIG. 1 is a rear perspective view of the arrow vane;

FIG. 2 is a right side view thereof;

FIG. 3 is a left side view thereof;

FIG. 4 is a front view thereof;

FIG. 5 is a rear view thereof; and

FIG. 6 is a top view thereof; and,

FIG. 7 is a bottom view thereof.

FIGS. 1-7 show features in broken lines. These features are shown for environmental purposes and do not form any part of the claimed design. Further, any broken lines immediately adjacent the solid-line portions of the design form the boundary of the design, with the broken lines forming no part of the claimed design.
